United States Patent

Des. 240,831

Patented Aug. 3, 1976

240,831

DENTAL FLOSS APPLICATOR

Hsio Wang, 2850 Citadel Drive NE,
Warren, Ohio 44483

Filed Oct. 28, 1975, Ser. No. 626,335

Term of patent 14 years

Int. Cl. D24—99

U.S. Cl. D24—1 D

FIG. 1

FIG. 3

FIG. 4

FIG. 5

FIG. 6

FIG. 1 is a top perspective view of dental floss applicator, showing my new design;

FIG. 2 is a top plan view thereof;

FIG. 3 is an enlarged fragmentary cross section taken on line 3—3 of FIG. 2;

FIG. 4 is an enlarged cross section taken on line 4—4 of FIG. 2;

FIG. 5 is an enlarged cross section taken on line 5—5 of FIG. 2; and

FIG. 6 is an enlarged cross section taken on line 6—6 of FIG. 2.

The broken line representations of the dental floss thread in FIGS. 2 and 6 are shown for illustrative purposes only.

I claim:

The ornamental design for a dental floss applicator, substantially as shown and described.
